UNITED STATES PATENT OFFICE.

NICOLA MARIA MARINARO, OF MONTREAL, QUEBEC, CANADA, ASSIGNOR OF ONE-HALF
TO JOHN LALLO, OF MONTREAL, CANADA.

STEP-LADDER.

1,235,711.

Specification of Letters Patent.

Patented Aug. 7, 1917.

Application filed December 21, 1914, Serial No. 878,377. Renewed June 22, 1916. Serial No. 105,298.

To all whom it may concern:

Be it known that I, NICOLA MARIA MARINARO, a subject of the King of Great Britain, and resident of 493 Ontario street east, 5 in the city of Montreal, Province of Quebec, in the Dominion of Canada, have invented certain new and useful Improvements in Step-Ladders; and I do hereby declare that the following is a full, clear, and exact description of the same.

The invention relates to improvements in step ladders, as described in the present specification and illustrated in the accompanying drawings that form part of the 15 same.

The invention consists essentially of the novel construction and arrangement of parts, whereby an additional frame folding to the main frame forms a support in the 20 open position of the ladder for the utensils of the worker.

The objects of the invention are to devise a convenient form of step ladder that will be particularly useful to cleaners and workmen generally, to insure safety for the person engaged at work, and generally to provide a simple and durable ladder that will meet all the requirements as furnished by a strong and steady scaffolding or stand.

30 In the drawings, Figure 1 is a perspective view of the ladder in its open position.

Fig. 2 is a vertical side sectional view of the ladder in its open position.

Fig. 3 is a vertical side sectional view of 35 the ladder in its collapsed position.

Fig. 4 is a detail showing a preferred form of connection between the supporting rear frames and the main ladder frame.

Fig. 5 is a plan view of a preferred form. 40 Like numerals of reference indicate corresponding parts in each figure.

Referring to the drawings, 1 are the steps extending between and secured to the uprights 2, said steps extending slightly beyond the front edges of said uprights 2, and said uprights at their upper ends and in the rear thereof having the recesses forming the shoulders 3.

4 are the rear props joined adjacent to 50 the lower end by the broad rail 6, said props at the extreme upper end thereof fitting under the shoulders 3 and joined to the uprights 2 by the link hinges 7, said links 7 being pivotally mounted over the plates 8 by the pivots 9, which extend through said

plates into the uprights, said plates 8 extending upwardly and in the open position of the ladder meeting at their upper ends and inner edges, the latter being flush with the inner edges of the uprights and props, the latter also meeting in the open position of the ladder.

It will be seen that the props and uprights are secured together by flexible hinges and that the plates and the said uprights and props meet in the open position of the ladder, in order to prevent the ladder spreading. The spreading of the ladder is also provided against by the bar hooks 10 secured to the uprights 2 and fastening into 65 the eyes 11 on the props 4.

12 are the side rails of the platform supporting frame at the rear joined together at the lower end by the cross rail 13 into which the pivots 14 extend through to the props 70 4 immediately above the rail 6.

The lower ends of the side rails 12 are preferably curved as shown in Fig. 4 and also the upper edge face of the cross rail 6. The pivots 14 are preferably off from the 80 center of the side rails 12 consequently in turning said rails 12 rearwardly the rail 13 binds on the rail 6 making the latter a support for the rails 12 and limiting the rearward movement of the rails 12.

Intermediate of the height of the rails 12 at the beginning of the reduced upper ends the cross rail 15 joins the said rails 12 and adjacent to the extreme upper end they are joined by the cross rail 16. The open frame 90 formed by the side rails 12 and cross rails 13, 15 and 16 folds closely to the props 4 and uprights 2, and at the upper end extends considerably above the ladder.

17 is a platform which is equivalent to the 95 top step of the ladder and is pivotally secured to the uprights 2 midway between the upper step and the extreme top ends of said uprights, said platform extending rearwardly considerably beyond the rear props 100 4 and therebetween and having at the under side at its outer rear end the parallel transverse strips 18 and 19 forming a channel or groove into which the cross rail 15 extends in the upper position of the ladder.

20 is a cleat adjacent to the front end and extending downwardly from the under side of the platform 17.

21 is a shelf hinged at the upper cross rail 16 and folding upwardly and outwardly 110

therefrom and supported by the brackets 22, the latter being pivotally secured on the said rails 12 in order to fold inwardly in the collapsed position of the said shelf. 5
23 is a hook secured to the rails 12 and fastening into the eye 24 on the shelf 21, so as to fasten said shelf securely in its collapsed position. 25 are ropes threaded through the uprights 2 at the upper end 10 thereof or otherwise suitably fastened thereto extending to the side rails 12 toward the upper end and secured thereto, said ropes having two functions that of safeguarding the platform 17 from falling through the 15 spreading of the open frame from the ladder and also as hand ropes in the event of any dizziness of the person using the ladder.

In Fig. 5 a means of permanently joining the side rails 12 of the open frame and platform 17 is shown in the looped wire 26 which is formed in V-shape and at the ends pivotally secured to the said rails and at the center pivotally joined to the underside of the said platform, thus avoiding the danger 25 incident to the spreading of the open frame and ladder proper and the consequent drop of the platform end. This is an addition not shown in Figs. 1, 2 and 3, as while important it is not a necessity in the construction. 30

In the use of this ladder for household or trade purposes, the person mounting the steps reaches the platform 17 which is safely supported as explained, by the pivot at the

front end and the open frame at the rear 35 end and on this platform the user stands to do the work, whatever it may be. The pail of water, rags, brushes and other accessories for cleaning are also supported on shelf 21.

The same may be done for calcimining, 40 whitewashing, painting or like work, and for the plumber and electrician, this furnishes a convenient place to rest his tools and materials, but hooks or other supporting devices may be used in place of this shelf, 45 and these would preferably be secured on the upper cross rail of the open flank, in fact changes may be made in the general construction of the ladder so long as the main features are retained, and which are 50 pointed out in the claim for novelty following.

What I claim as my invention is:

A step ladder comprising a step section and a prop section hinged together, a platform pivotally secured at the upper ends of said sections, a platform support pivotally secured to said prop section and a looped wire pivotally joining the under side of said platform with the uprights of said 60 platform support.

Signed at the city of Montreal, Quebec, Canada, this second day of November, 1914.

NICOLA MARIA MARINARO.
